ROTARY PLUGGING TOOL

Henri Lentulo, Paris, France

Application April 2, 1932, Serial No. 602,694
In France December 14, 1931

4 Claims. (Cl. 32—51)

The present invention relates to rotary plugging tools for the introduction of plastic materials into cavities having narrow openings. It is more particularly intended for use in the art of dentistry for the plugging or stopping of dental channels, as described in my prior U. S. A. Patent 1,771,182, issued July 22nd, 1930.

This plugging tool is employed in dentistry as an instrument for the introduction of pastes, cements and various plastic materials intended for the stopping of cavities having narrow mouths or orifices, especially the root channels or nerve cavities of teeth which have suffered partial destruction, intentional or spontaneous, of the vascular and nervous matter which normally filled them.

The present invention consists of an improved rotary plugging tool, characterized in that the wire of which it is formed, instead of being wound helically around a theoretical core for the whole of its length and being of circular cross section as far as its extremity, as in the rotary plugging tool of my prior invention, is so constituted as to receive in the terminal portion, onward from the point where its thickness is sufficiently reduced, a suitable angular cross-section, being at the same time twisted around its axis without any theoretical or imaginary core; this construction allows the introduction of the improved instrument as far as the very end of the cavity to be filled without any preliminary opening out or broaching of this cavity and provides for sure and certain propulsion of the filling or stopping material as far as the extreme limit of the cavity.

The invention is hereafter described with reference to the accompanying drawing, in which:—

Figure 1 represents a rotary plugging tool made in accordance with my prior Patent 1,771,182 and mounted in a chuck for driving purposes.

Figure 2 illustrates the application of the instrument to a tooth, shown on an enlarged scale.

Figure 3 represents the improved plugging tool according to the present invention, this figure being a greatly enlarged view of the working length of the instrument.

Figures 4 and 5 illustrate in cross section suitable formations for the point section of the improved plugging tool.

As shown in Figure 1, the rotary plugging tool of my prior patent specification comprised a helicoidal coil of wire *f* secured to or integral with a shank or mandrel *M* intended to transmit the rotary drive received from a dental engine or other motor, the shank *M* being held for example

in a chuck *c*. The latter can be mounted in the usual way in a supporting hand-piece *d*. Figure 2, at the end of the flexible shaft *e* of the dental engine or the like.

The general shape of the instrument corresponds approximately to the shape of the space to be filled with the pasty material, cement, etc., as will be seen from Figure 2, which represents the rotary plunger introduced into the root channel of a tooth.

The wire coil *f* was wound helically around an imaginary core for substantially the whole of its length, terminating in a slightly drawn-out coil, not clearly defined as a geometrical spiral, so that the point did not always fulfil its purpose of transporting the plastic material to the very end of the cavity in the tooth *T*. Unless the cavity was sufficiently wide to admit the coil *f* almost up to the apex of the root, or at least sufficiently wide to admit a dental broach for clearing and enlarging the cavity to receive the coil *f*, there would remain a narrow extremity channel (often of capillary dimensions) unfilled with the plastic material and therefore liable to harbour infective matter and micro-organisms entering from the apex.

The improved rotary plunger (see Figure 3) is formed from a thin metallic wire *a* of circular cross-section, of a diameter of approximately some hundredths of a millimetre, which diameter decreases gradually towards the free end or point, the other end or shank *a*¹ being secured in a chuck *c* which can be clamped in the hand-piece *d* in any suitable manner, as in the case of my prior invention. The chuck *c* is therefore shown in dotted lines in Figure 3, to indicate that the mode of drive may remain unchanged.

The wire *a* is wound helically to a varying pitch around a theoretical core, the diameter of which varies likewise, so that it is not constantly cylindrical, but assumes generally a tapering conical shape like a rat-tail, the widest part being at the base adjacent to the shank *a*¹.

Moreover, as will be seen from Figure 3, the improved rotary plunger comprises two associated parts:

(1) A first portion generally indicated as *A*, constituted by the metal wire *a* of tapering circular cross-section, coiled in a spiral upon an imaginary core, like the point section of the rotary plunger in my previous invention and of trunco-conical shape as indicated by the chain lines *x x'* and *y y'*; and

(2) A second portion or point section, generally indicated as *B*, of suitable length, and forming

105

110

a prolongation of the part A; this portion B instead of having the shape of a final drawn-out coil as in the instrument described in my aforementioned prior specification, is constituted by 5 the twisted extremity of the wire *a* of the section A, to which there is given a suitable angular (i. e. non-circular) cross section, for example square (*b*, Fig. 4), triangular (*b'*, Fig. 5) or other. The alteration of cross-section and the change 10 from spiral coiling to twisting, at the junction of the two portions or sections A B will be seen to begin from the point where the thickness or overall diameter is sufficiently reduced to allow introduction into root channels of minimum dimension. 15

In this second section B, the wire is merely twisted around its axis $z-z'$, in the same direction or "hand" as the spiral coiling of the portion A, but without being coiled around a core, and 20 the corners of the angular cross-section are exposed while the sides of the cross-section form helical flutes in which the plastic material collects.

Thus the point section B has no final drawn-out coil like my previous instrument, but has the twist continued right up to the extremity, which 25 enables it to act as means for transporting the plastic material into the very end of the cavity when introduced into the root channel of a tooth 30 T, as in the case of Figure 2. Moreover, since the point section is of less diameter than the small end of the coil, it can be passed much further into the cavity; in fact the point section can be introduced just as far as a dental broach of equal 35 size, so that the preliminary widening out of the cavity by the removal of sound material is rendered unnecessary.

The plugger being given a movement of rapid 40 rotation, by means of the ordinary dental engine, while supported in the hand-piece *d*, the stopping material will be propelled into the channel by the combined action of the two portions or sections A B.

It may be pointed out that the root channel 45 to be filled is practically closed at its apical extremity, so that at most the stopping material will only be propelled as far as the instrument penetrates; beyond that point, the air remaining 50 between the extremity of the rotary plugger and the apical end of the channel will oppose the intrusion of the stopping material.

Rotary plugging tools cannot therefore possess 55 their maximum efficiency unless they can be introduced right up to the end of the cavities to be plugged. In order that this essential condition shall be fulfilled, it has hitherto been necessary to broach out and to widen the root channel as far as its extremity, sufficiently to allow the introduction of the plugging tool into the entire 60 space to be filled. This preliminary clearing out or broaching encounters great difficulties, particularly by reason of the shape of the root channels, which are not always straight, but more or less curved, especially at their inner terminal 65 end. It is quite impossible to straighten out this profile and it can only be widened by broaching or the like; moreover this widening is frequently impossible by reason of the small dimensions of the channel and the hardness of the walls. It follows therefore that the rotary plugger described in my prior specification, although of extremely small dimensions, often does not reach the end of the channel to be filled; it 70 results for the reason explained above that there

is a fault or gap in the plugging, at the very region where this defect is most formidable.

The present invention provides an instrument 80 consisting of a rotary plugger of improved type, which enables the dentist to introduce the paste, cement or the like with absolute certainty into the entire length of the root channel, without it being necessary first to widen out the apical extremity of the latter, and the principal condition upon which the efficiency of the apparatus depends, is thus fulfilled without encountering the great difficulties explained above. 85

The twisted shape given to the wire in the portion B, allows, by reason of its tenuity or thinness, the introduction of this portion B as far as 90 the very bottom of the root channel of the tooth under treatment, whatever be the shape and the fineness of the channel, and without any preliminary broaching or widening of this channel.

On the other hand, after the paste or cement 95 has been propelled by the coiled portion A of the instrument as in my previous rotary plugger, the twisted portion B continues this propulsion of the material with certainty as far as the extreme limit of the cavity, the twisting of the wire which constitutes this portion B being continued right up to its extremity without any break. 100

Consequently the improved rotary plugging tool as herein described provides effective means for attaining the objects explained above. It will be 105 evident that the use of the invention is not limited to dental purposes, but that the improved plugging tool may be employed for the filling or introduction of plastic materials into cavities in general, where the mouth or opening is narrow so 110 that difficulty is met with in ensuring the penetration of the material to the bottom of the cavity.

What I claim is:—

1. A rotary plugging tool of the character described, comprising a wire coiled for a portion of its length as a tapering helix and twisted for another portion of its length in the same direction around its own axis, said twisted portion being of non-circular cross-section and extending 115 from the smaller end of said helix to an extremity of said wire.

2. A rotary plugging tool of the character described, comprising a flexible wire of varying cross-section, one extremity of said wire forming 120 a shank, an intermediate portion of said wire being coiled to a tapering helix having its axis in prolongation of the axis of said shank, and an extremital portion of said wire twisted around its 125 own axis, said extremital portion being of angular cross-section and twisted to form flutes of the same hand as said tapering helix and having its axis normally in prolongation of the axis of said helix. 130

3. A rotary dental plugging tool, comprising a 135 point section, a shank, and an intermediate portion, all made from a continuous length of fine wire, said point section being of non-circular cross-section and twisted about its own axis, said shank being adapted for receiving rotary motion, 140 and said intermediate portion being coiled to a tapering helix of the same hand as the twist of said point section with its smaller end adjacent to said point section and its larger end adjacent 145 to said shank, said point section having its axis normally in prolongation of the axes of said shank and of said intermediate portion but being flexible to follow the shape of a dental cavity, into which plastic material will be fed by rotary movement 150

of said intermediate portion and point section acting on the inclined plane principle.

4. In a dental plugging tool comprising a wire coiled for a portion of its length as a tapering helix with a rotatable shank formed axially of said helix at the larger end thereof, a point section extending axially of said helix from the

smaller end thereof, said point section being of angular cross-section, twisted around its axis to form helical flutes of the same hand as said helix, said point section being of a diameter not exceeding half the smallest diameter of said helix. 80
